UNITED STATES PATENT OFFICE.

WILLIAM L. SILVEY, OF LIMA, OHIO.

DYNAMO-ELECTRIC MACHINE.

SPECIFICATION forming part of Letters Patent No. 399,088, dated March 5, 1889.

Application filed October 1, 1888. Serial No. 286,828. (No model.)

To all whom it may concern:

Be it known that I, WILLIAM L. SILVEY, a resident of Lima, in the county of Allen and State of Ohio, have invented certain new and 5 useful Improvements in Dynamo-Electric Machines, of which the following is my specification.

My invention relates principally to certain details in mechanical construction, which, 10 although of comparative insignificance mechanically, still when taken into consideration electrically are of great importance.

This invention relates principally to a dynamo which I have been building for several 15 years, in which the armature is disposed above instead of below the field-magnet coils, or as is usually employed in some of the well-known dynamo machines built in this country and in Europe.

20 Referring to the accompanying drawings, which are made a part hereof, similar letters referring to similar parts throughout, Figure 1 is a side elevation, in perspective, of my completed dynamo-electric machine. Fig. 2 is an end elevation in perspective, looking from the commutator end of Fig. 1. Fig. 3 shows one of my field-magnet castings partly in section, the wire being removed; and Fig. 4 shows the flange of brass or other non-magnetic metal, whose purpose is to hold the 25 field-magnet coils in place on the inside of the coils when they face each other. These flange-plates are screwed to the face of the pole-piece, for it is a well-known fact that the 30 pole-pieces C of the field-magnets B must not approach too near each other, for there would then be too great a magnetic loss. For this reason the pole-pieces of a three-hundred-light 35 machine should not approach nearer than 40 about four inches to each other. In order to make the field-magnet cores come into exact position each time, I drill a hole in the exact center of the base, into which I drive the turned pin F. This pin fits into a corresponding 45 hole in the base A, thus making the field-magnets self-centering. In other words, this pin F acts as a steady-pin to keep the field-magnet cores a certain specified distance apart. This, while apparently of insignifi- 50 cant importance, becomes one of vital importance when considered from a mechanical standpoint; but the point of most importance

in the construction of these fields is a saving of magnetism—or, in other words, creating a nearly perfect magnetic joint, when there will 55 be little or no loss magnetically. To accomplish this, I cast on the lower end of my field-magnet core B the extra-heavy flange head or plate D. The objects of this heavy end plate are several—one to keep the coils firmly together, and take up the magnetism of the end of the coil and the end of the plate. Being turned off perfectly smooth, it offers a very large contact-surface between the magnets and the base A, which makes the loss at this place practically *nil*. At the upper end of the field-magnet coil, directly against the pole-piece, I expand this pole-piece C into the flange C'. The 60 object of this flange or expansion is to gather up the magnetism of the top end of the coil 70 and divert it into the pole-piece of the machine, where it is consequently carried into the armature and the proper channel. The base A is of the ordinary oblong form—such as I have been building for the past five or six 75 years—the bearings being of the ordinary split box and an A-shaped bracket at each end. The armature is of the ring-type and of the closed-circuit style, connected to a collector of the ordinary style and in the usual way. 80

Having fully described my invention, what I claim as new, and wish to secure by Letters Patent of the United States, is my peculiar construction of the upright two-column field-magnets, by which I greatly simplify the 85 construction of the parts and utilize the greatest amount of the magnetic energy for useful purposes, to wit:

1. In an upright field-magnet for dynamo-electric machines, the field-magnet core B, 90 cast solid, the pole-piece C, and flanges C' D, in combination with the supplementary flange-plate e, for holding the wire in place and collecting and distributing the magnetism of the coils, as set forth.

2. The field-magnet for a dynamo-electric machine, the pole-piece C, and the expanded flange C', cast solid, the front part, e, of a non-magnetic material, secured thereto by screws, as set forth. 100

3. In a dynamo-machine having salient poles, the combined base and heel plate A, upright field-magnets B B, their lower ends expanded into flanges D D, their upper ends

forming pole-pieces C C, and flanges C' C' and *e e*, for holding the coils of wire in place, as set forth.

4. The combination, in the field-magnet core of a dynamo-electric machine, of the field-magnet core B, and the flange - piece D, cast thereon, and forming a connecting-block for joining the magnet to the base and heel-plate A, the upper end of the core D expanded into

the pole-piece C, having a flange, C', as a part ¹⁶ thereof, the flanges, pole-pieces, and core cast in one piece, to which a supplementary flange, *e*, is secured, as set forth.

WILLIAM L. SILVEY.
